UNITED STATES PATENT OFFICE.

GEORGE LOUIS RICHARDS, OF MALDEN, MASSACHUSETTS, ASSIGNOR TO STANDARD COMMERCIAL COMPANY, OF BOSTON, MASSACHUSETTS, A CORPORATION OF MAINE.

BARREL-HEAD FASTENER.

No. 872,749.

Specification of Letters Patent.

Patented Dec. 3, 1907.

Application filed October 24, 1905. Serial No. 284,247.

To all whom it may concern:

Be it known that I, GEORGE LOUIS RICHARDS, a citizen of the United States, and a resident of Malden, in the county of Middlesex and Commonwealth of Massachusetts, have made certain new and useful Improvements in Barrel-Head Fasteners, of which the following is a full, clear, and exact description.

10 The object of my invention is the construction of a fastening device for barrel-heads capable of being driven down into the barrel-chimes substantially with the grain thereof and approximately at right angles to the barrel-head surface, and which will at the same time have so strong a hold in the wood as to lock the barrel-head in place with the maximum of security.

It is self evident that fastening devices 20 driven in with the grain of the wood pull out very easily. Especially is this true when the force to be resisted lies in the same direction. The consequence has been that inventors, in seeking the best method of fastening barrel-heads in place, have made no attempt at devising fasteners to be used in such a manner, but have either constructed them to be driven into the barrel-staves parallel with the barrel-head surface, or have arranged 30 them to engage the barrel-hoops. None of them have proved satisfactory, however, either because of lack of economy in manufacture, difficulty in application, or insecurity in hold upon the barrel-head.

35 In the course of my experiments, I discovered that it was possible to drive a fastening device in with the grain of the staves, and yet have it resist removal far more than any of the types of fastening-devices which I 40 had been able to subject to test. The first and most important feature of my discovery was that by having the outward pressure of the barrel-head resisted by a member or section joined to the drive-section at an angle 45 of approximately forty-five degrees, such a lateral pressure is given to the latter as to greatly increase its frictional hold in the barrel-stave.

50 My second improvement consists in so diverging the directions of driving of the two drive-sections as to still further increase

their lateral pressure against their confining wood-fibers.

A further improvement consists in forming each drive-section with a rearward bend at 55 its upper portion disposed to more fully brace the same against the pressure given by the barrel-head.

My final improvement relates to means for enabling the fastening device to be more 60 readily driven into the barrel-stave by means of an ordinary hammer.

Referring to the drawings forming part of this specification, Figure 1 is a sectional elevation of a portion of a barrel showing one 65 of my improved fastening devices in side view. Fig. 2 is a perspective view of one of the fastening devices upon an enlarged scale. Fig. 3 is a side view of the same. Fig. 4 is a rear elevation of the device. Fig. 70 5 is a front elevation of the device showing it driven into a barrel-stave and pressing upon the barrel-head.

The fastening device is formed from a length of suitable wire, the ends of which 75 compose the drive-sections 1, the intermediate portion of which becomes the pressure-bar 4, and the connections 3 between the latter and the upper ends of the drive-sections are the angular brace-sections. 80

As shown in Figs. 1 and 5, the brace-sections 3 descend from the upper ends of the drive-sections 1 at approximately forty-five degrees therewith, and present the pressure-bar 4 to the barrel-head 12 at a substantial 85 distance below the points where the drive-sections enter the chimes 11 of the barrel-staves 10. Consequently any outward movement given to the barrel-head acts against the pressure-bar 4 through the brace-sections 3 90 to force the upper part of the drive-sections back against the confining walls of the holes in which they have been driven. Hence, such pressure being a lateral instead of a longitudinal one, the fastening devices will not 95 be started even when a heavy weight rests upon the barrel-head with the barrel upside down.

As shown in Figs. 2 and 4, the upper extremities of the drive sections 1 are normally 100 in contact, or nearly so, while their sharpened points are somewhat widely separated. By

means of this angular divergence, the points in the stave entered by one of the devices are much farther apart than the original distance between the upper extremities of the 5 drive-sections. Further, as the drive-sections penetrate the wood they continue in the divergent directions in which they are started, thereby forcing them farther and farther apart. Consequently when the 10 device has been driven home, the drive-sections are so widely separated as to receive a powerful pressure one toward the other given by the resilient flexure of the pressure-bar 4 and the brace-sections 3. This pressure still further increases the frictional 15 resistance to the withdrawal of the fastening device.

By having the upper ends of the drive-sections thus normally close together they are 20 still near enough together when they have been nearly driven home to have both bends 5 come beneath the hammer used for the purpose. This permits of the device being driven in place with a single blow of an ordinary hammer, the same as a nail.

The rearward bends 2 at the upper ends of the drive-sections 1 act by the slight compression which they give to the wood-fibers behind them, and by the increased bracing 30 action which they give to the push from the pressure-bar 4, to still further insure the fastening device from yielding and permitting the barrel-head to escape.

It should also be noted that by having the 35 drive-sections comparatively long, the fastening device is not only made to be held more firmly in the wood, but the length permits of its being more conveniently grasped and held between the thumb and fingers of 40 the left hand while being driven in place. The devices which are designed to be driven horizontally through the barrel-staves must necessarily be rather short, and hence fail of both these desirable characteristics.

45 These fastening devices being formed from wire, and but a short length thereof at that, with a minimum number of bends, are economical to manufacture; and, as shown above, are convenient and easy to apply, 50 with the maximum of staying ability.

What I claim as my invention and for which I desire Letters Patent is as follows, to wit:—

55 1. The combination with a barrel, of a barrel-head fastener constructed with a drive-section disposed for being driven into the barrel-chime substantially parallel with the grain of the wood; and a brace-section at the upper end of said drive-section arranged to 60 brace between the upper surface of the barrel-head and the barrel-chime, and by such bracing action to aid said drive-section against removal from the chime into which it is

driven; the face of said brace-section where it contacts with said barrel-head being horizontally extended parallel with the surface of such chime. 65

2. The combination with a barrel, of a barrel-head fastener consisting of a single length of wire having the terminals thereof compose 70 the drive-sections designed to be driven into the barrel-chime substantially parallel with the grain of the wood; having the central part compose the pressure-bar for contacting with the barrel-head, and the remainder 75 thereof compose the connections between said pressure-bar and drive-sections; said connections being the brace-sections and lying in a plane at an angle with the drive-sections; and the length of said drive-sections 80 being a plural number of times longer than said brace-sections, in order that the former may securely hold their position.

3. A barrel-head fastening device consisting of a single length of wire the terminals of 85 which compose the drive-sections, and the intermediate part of which is constructed to rest against the surface of the barrel-head; said drive-sections making an acute angle one with respect to the other. 90

4. A barrel-head fastening device constructed to be driven in with the grain of the barrel-staves; the same being formed from an elongated length of metal the terminals of 95 which compose the drive-sections and the intermediate part of which is constructed to rest against the surface of the barrel-head; said drive-sections having their upper ends approximately in contact and their lower end separated to a substantial distance from 100 each other.

5. A barrel-head fastening device constructed from a length of wire formed with drive-sections, pressure-bar, and brace-sections between the latter and said drive-sections; said drive-sections being in substantial contact at their upper ends but substantially separated at their lower ends. 105

6. A barrel-head fastening device constructed from a length of wire formed with 110 drive-sections, pressure-bar, and brace-sections between the latter and the drive-sections; the upper parts of the drive-sections being each given a backward bend.

7. A barrel-head fastening device constructed from a length of wire formed with drive-sections, pressure-bar and brace-sections between the latter and the drive-sections; the drive-sections being in substantial contact at their upper ends. 115

8. A barrel-head fastening device constructed to be driven in with the grain of the barrel-staves; the same being formed from a single length of wire the terminal parts of 120 which compose drive-sections, the central part is a pressure-bar, and the remainder of 125

which are brace-sections extending from the latter to the upper ends of the drive-sections at angles of approximately forty-five degrees relative thereto; the upper ends of said drive-sections being substantially in contact and bent backward relative to the pressure-bar, and the lower ends of the drive-sections being separated one from the other.

In testimony that I claim the foregoing invention, I have hereunto set my hand this 10
21st day of October, 1905.

GEORGE LOUIS RICHARDS.
